UNITED STATES PATENT OFFICE.

JOCELYN EMILE OLLIVIER, OF LA VIGNETTE, ST. GERVAIS LES BAINS, FRANCE.

PROPELLER MECHANISM.

1,393,157.

Specification of Letters Patent. Patented Oct. 11, 1921.

Application filed May 7, 1918. Serial No. 233,136.

(GRANTED UNDER THE PROVISIONS OF THE ACT OF MARCH 3, 1921, 41 STAT. L. 1313.)

To all whom it may concern:

Be it known that JOCELYN EMILE OLLIVIER, a citizen of the French Republic, residing at La Vignette, St. Gervais les Bains, 5 country of France, has invented new and useful Improvements in Propeller Mechanism, (for which I have filed applications in France, December 6, 1916, March 19, 1917, June 29, 1917, and November 6, 1917, 10 and in England, March 11, 1918, Patent No. 130,677,) of which the following is a specification.

This invention relates to tractors, and has particular reference to propelling mechanism 15 therefor of the type wherein an endless track which travels over the surface of the ground and track-bearing members for maintaining the lower portion of or run of the track in contact with the surface of the 20 ground are employed.

The present invention has as its main purpose to provide a propelling mechanism of this type wherein all of the track-bearing members will bear upon that portion of the 25 track in contact, at any given instant, with the ground with equal pressure whatever may be the nature of the ground, so as to obtain proper adherence or traction between the endless track and the surface traversed, 30 and to eliminate, or at least minimize, all shocks or excessive strains which otherwise might prove injurious to the propelling device.

The present invention contemplates, 35 broadly, a propelling mechanism of the type having an endless track, successive portions of which come into contact with the ground, track bearing members forming a guide rail, which bearing members maintain the 40 track in contact with the ground and travel upon the endless track as the latter is laid, and means comprising, in the present instance, a fluid body in co-operative relation with all of said track-bearing members for 45 maintaining all of said members with equal pressure against the endless track irrespective of any qualities or undulations in the surface of the ground traversed.

In the following specification, I have described in detail, and in the accompanying drawings have shown several embodiments 50 of my invention and changes which may be made therein, but it is to be understood that the present disclosure is illustrative only

and is in no way restrictive of my invention.

In the accompanying drawings:

Figure 1 is a side view of one embodiment of my improved propelling mechanism,

Fig. 2 is a transverse sectional view of 60 the propelling mechanism shown in Fig. 1 and taken on line 2—2 of Fig. 1,

Fig. 3 is an enlarged fragmentary longitudinal view, partly in section, of a propelling mechanism in which the fluid body 65 is housed in a rigid casing,

Fig. 4 is a transverse sectional view taken on line 4—4 of Fig. 3,

Fig. 5 is a fragmentary side view of another embodiment of my invention, 70

Fig. 6 is a sectional view taken transversely through Fig. 5.

In the drawings like numerals represent like parts in the several views.

In the present illustrative disclosure of 75 my invention I have shown the bearing members for the endless track, designated by the character A, as comprising rollers B, which rollers are in alinement with each other so as to form a sectional bed or rail 80 which guides the lower run of the endless track A, and which at the same time roll over the track as the vehicle advances. The means for equalizing pressure with which the several track-bearing members B maintain the track A in contact with the surface of the ground, comprises, in the present instance, a body fluid designated generally by the letter C.

The track-bearing members may be of any 90 suitable form or construction and may be connected to the propeller frame and interposed between the fluid body and the track in any suitable manner, and the endless track itself may be of any desired construction. 95 The body fluid may be confined in any suitable manner and if desired, more than one body of fluid may be employed.

In the embodiment of my invention shown in Figs. 1 and 2, the frame of the propelling device is disclosed as comprising two parallel sills or beams designated by the numeral 30, these beams curving upwardly at their forward ends to permit the endless track to come into contact with the ground 100 at a slight angle and so that the vehicle may ride over a rise or obstruction in its path.

The frame may be connected to the vehi-

cle in any suitable manner, but by way of illustration I have shown for this purpose cross bars 31 which are attached at one end to the chassis of a vehicle (not shown) and at their outer end pass beneath and are secured to the sills 30. It is, of course, understood two propelling mechanisms are usually employed for each vehicle.

Each of the track-bearing rollers B of Figs. 1 and 2 are shown as being rotatably carried in the lower ends of a pair of arms 32 pivotally connected at their upper ends to the sills 30 by means of pins 33. Between the arms 32 of each pair is a stirrup 34 or inverted U-shaped member having its lower ends hingedly connected to the arms 32, intermediate the ends of the latter, by means of the pins 35. Each of the stirrups carry a plate 36 which bears against the fluid body C. In the present instance, the body of fluid is confined within an elongated flexible envelop 37 which may be formed of double rubberized fabric and filled with air under pressure. Any suitable fluid may be used. A valve 38 may be provided for the purpose of inflation and, of course, the vehicle or propelling device may carry a compressed air reservoir for inflating the bag or envelop.

To prevent the fluid body from bulging bodily upwardly, when strain is exerted thereon by upward pressure on the track, a plate 39 is positioned immediately above the envelop 37. To vary the size of the space between the plate 39 and the plates 36, the plate 39 is arranged to be adjusted vertically with respect to the frame or sill 30, and for this purpose any desired form of mechanism may be employed. In the present instance, the plate 39 has an upwardly extending threaded rod 40 on which is threaded a nut carrying a worm gear 41 located between a plate 42 and an arch 43 carried by the plate 42. The plate 42 is adjustably connected to the chassis of the vehicle by rods or beams 44, it being remembered that the cross bars 31 are also secured to the chassis and serve to support the vehicle load. Coöoperating with the gear 41 is a worm 45, and when the latter is rotated the plate 39 will move vertically. If preferred, the worm 45 may be connected up by means of a suitable transmission mechanism to the source of power of the vehicle. To maintain the plate 49 in proper position over the fluid body C, the plate has upwardly extending guide pins 46 working in openings in the fixed plate 42.

To limit downward movement of the track-bearing members or rollers B, a bar or strip 47 is provided, this strip being connected at its opposite ends to the plate 39 and passes beneath the resilient body and the cross members of each of the stirrups

34. Springs 48 may be interposed between the strip 47 and the cross members of the stirrups 34 to prevent the rollers from suddenly dropping onto the track when the device is passing over unusually rough ground.

The endless track A shown in Figs. 1 and 2 may be formed from an ordinary endless chain with shoes 49 connected across its links to assure adherence with the surface of the road traversed. The endless track passes in a vertical plane entirely about the propelling device and to guide the upper run of the track guide rollers 50 and 51, carried at opposite ends of the plate 39, are employed. To hold the upper run of the track taut these rollers are yieldingly maintained against the chain by springs 52 and 53, respectively. The rollers guiding the upper run of the endless track may vary in number and may be pivotally connected as is the roller 50, or slidably carried as is the roller 51.

The endless track A may be caused to be moved about the propelling device in any approved manner, but, preferably, one or more of the track-bearing rollers may be positively driven.

In Fig. 1, the pinions 54 are driven, these pinions having radially extending teeth 55 which fit between the links of the endless track. Mounted upon the spindles or shafts 56 to which the pinions 54 are fixed, are sprocket wheels 57, and fixed to the drive shafts 58 which are in axial alinement with the pivots 33 are driven sprocket wheels 59. Passing about the sprocket 57 and 59 are sprocket chains 60. If desired, the shaft 58 of the rear driving mechanism may be employed to drive the device forwardly, and the front pinion may be employed to drive the device rearwardly, but, of course, this is optional.

If preferred, the foremost roller B may be maintained against vertical movement, and this is desirable on certain kinds of roads.

The operation of the propelling device shown in Figs. 1 and 2 will be readily understood from their foregoing description. The pinions 54 are driven to cause the track to travel about the propelling device, and as the device advances successive portions of the track are laid and the rollers B travel over the track. The rollers are maintained in contact with the track by means of the fluid body C. In the event that the fluid employed is a gas, such as air, which has a tendency to expand indefinitely, the rollers are maintained elastically or resiliently against the track. If the surface of the ground traversed is level and has no qualities, the upward pressure upon the track-bearing members which engage that portion of the track which is at that instant, in con-

- tact with the ground, have their plates 36 bearing with equal and unvarying pressure against the fluid body. In the event the device passes over a rise or undulation, the rollers 5 are successively forced upwardly and, therefore, the plate of that roller which is passing over the rise initially bears with greater pressure against the fluid body than the plates 36 of the remaining bearing members, and will sink into the fluid body. However, due to the principle of the so-called transmissibility of fluid pressure, the pressure applied to any area of the surface of the confined fluid body will become equally 10 felt over every other equal area of the surface. Therefore, in the present instance, the pressure exerted by one of the plates against the fluid body C will be immediately transmitted to each of the other plates in contact 15 therewith, and as the roller members B have movement relatively to the frame each of these members are caused to press with like pressure against the chain. Thus the pressure upon the chain is equally distributed 20 and that portion of the chain in contact with the ground bears with equal pressure throughout its length against the ground irrespective of inequalities therein. The result is that proper traction between the endless track and the ground is always obtained. Furthermore, since the stress to which one 25 of the track bearing members is subjected is immediately transmitted in part, to each of the other track-bearing members so that the strain on all of the track-bearing members is equal, shocks and blows which otherwise would occur when the device is passing over any inequalities in the road are largely 30 minimized.
- 40 It is, of course, evident that the body of fluid may be confined in any suitable manner, and by way of further illustration, I have shown in Figs. 3 and 4 the envelop 37 as being housed within a metallic casing 61, this casing having a plurality of spaced cylinders 62 in its lower wall, in which are 45 adapted to slide pistons 63 carried by stirrups 34^a, which in turn are connected to the arms carrying the rollers B. The metallic tube or casing is closed at its opposite 50 ends, and it may be of any suitable cross section.
- The structure shown in Figs. 5 and 6 is similar to that illustrated in Figs. 1 and 2, 55 but in this instance the stirrup 34^b which carries the plate 36^b is mounted on the extension of the arms 32^b bearing the rollers.
- It is to be understood that my invention is susceptible to various modifications and 60 changes which would be within the spirit of the invention without departing from the following claims.
- What I claim is:
1. In a propelling mechanism, an endless track, rollers forming a guide rail for said
- track and adapted to roll thereupon as successive portions thereof are laid upon the ground, a flexible envelop inflated with air, and means for associating said rollers with said envelop so that the air within the same 70 will cause the rollers to bear with equal pressure against the track.
2. In a propelling mechanism, an endless track, track bearing rollers forming a guide rail for the track and adapted to move over 75 the same as successive portions thereof are laid upon the ground, a compressible fluid body, a flexible envelop about said body, a rigid casing housing said flexible envelop, and means for associating said track bearing 80 rollers with said fluid body so that the rollers are maintained resiliently against the track and with equal pressure.
3. In a propelling mechanism, a frame, an endless track about the frame, track bearing 85 members movably mounted on the frame, a fluid body associated with said track bearing members to cause them to resiliently maintain the track against the ground, means for exerting a downward pressure on 90 said fluid body, and means for vertically adjusting said last mentioned means relative to the chassis of a vehicle.
4. In a propelling mechanism, a frame, an endless track about the frame, track bearing 95 members pivotally mounted to said frame and adapted to form a guide rail for the lower run of said track, a fluid body associated with said track bearing members, a confining plate for said fluid body, and 100 means for adjusting said confining plate relative to said frame.
5. In a propelling mechanism, a frame, an endless track about said frame, vertically 105 movable arms carried by said frame, bearing members carried by the lower end of said arms and engaging the lower run of said track, a fluid body, plates bearing against said fluid body and adapted to sink therein, and connections between said plates and said 110 arms.
6. In a propelling mechanism, a frame, an endless track about said frame, arms pivoted to said frame, rollers rotatably carried by said arms and forming a guide rail for the 115 lower run of said track, a fluid body, plates bearing against said fluid body, and connected between said plate and said arms.
7. In a propelling mechanism, a frame, an endless track, a fluid body, arms pivoted to 120 said frame, rollers rotatably carried by said arms and forming a guide rail for said track, members carried by said arms intermediate their ends, and plates carried by said members and engaging against said fluid body 125 so that the fluid body will resiliently urge said rollers against said track.
8. In a propelling mechanism, a frame, an endless track about said frame, arms pivotally connected to said frame, rollers rota- 130

4
tably carried by said arms and forming a
guide rail for the lower run of said track,
stirrups carried by said arms, plates carried
by said stirrups, and a compressible fluid
5 body against which said plates bear whereby
said rollers are resiliently urged against the
lower run of said track.

9. In a propelling mechanism, a frame, an
endless track about said frame, arms pivot-
10 ally connected to said frame, rollers rota-
tably carried by said arms and forming a
guide rail for the lower run of said track,
stirrups carried by said arms, plates carried

by said stirrups, and a compressible fluid
body against which said plates bear whereby 15
said rollers are resiliently urged against the
lower run of said track, and means for driv-
ing at least one of said rollers so as to im-
part movement to the mechanism.

In testimony whereof I have hereunto set 20
my hand in presence of two subscribing wit-
nesses.

JOCELYN EMILE OLLIVIER.
